UNITED STATES PATENT OFFICE.

THOMAS BROADBENT, OF SCHENECTADY, NEW YORK, ASSIGNOR TO GENERAL ELECTRIC COMPANY, A CORPORATION OF NEW YORK.

TURBINE-NOZZLE.

973,472.

Specification of Letters Patent. Patented Oct. 25, 1910.

Application filed March 28, 1908. Serial No. 423,809.

To all whom it may concern:

Be it known that I, THOMAS BROADBENT, a subject of the King of Great Britain, residing at Schenectady, county of Schenectady, State of New York, have invented certain new and useful Improvements in Turbine-Nozzles, of which the following is a specification.

The present invention relates to nozzles or fluid discharging devices for elastic fluid turbines. Its object is to improve the construction of such nozzles and to provide nozzles which can be economically manufactured, readily assembled, and that will perform their functions in an efficient manner.

In the accompanying drawing illustrating one of the embodiments of my invention, Figure 1 is a perspective view of a group of nozzle members with part of the holder for the same broken away; Fig. 2 is a sectional view of a portion of a turbine showing the relation of the nozzle to the buckets; Fig. 3 is a diagrammatic view showing the nozzle in section and illustrating the manner in which the motive fluid is directed against the buckets; Fig. 4 is a sectional view through a nozzle and a holder of a slightly modified form; and Fig. 5 is a perspective view of an alternative form of nozzle member.

The invention is illustrated as applied to an axial flow turbine but it can be applied to other types of turbines. In an axial flow turbine the wheel or rotor 1, mounted on a shaft (not shown) to move therewith, carries one or more rows of buckets 2 on its periphery. If more than one row of buckets are employed, intermediate or stationary buckets 3 are secured to the turbine casing 4 and project between the rows of buckets 2. The number of wheels will be varied to suit the operating conditions to be met by the turbine, and nozzles will be provided for delivering steam from the source of supply to the initial wheel and, in a stage machine where a number of wheels are employed, from that wheel to the next and so on. Mounted upon the wall of the turbine steam chest or upon the diaphragms 5 between the successive stages of the turbine and secured in position by bolts or other devices are holders 6 by which the nozzles are held in proper relation to the buckets. The inner holder may, if desired, be formed integral with the diaphragm 5. These holders are provided with shoulders 7 with which the flanges 8 of

the nozzle members engage and between which and the adjacent surface of the wall or diaphragm these flanges are held, but other means of securing the flanges to a support may be employed under other conditions.

The individual members 9 are arranged in nested relation in groups and direct the steam flowing from the space above the diaphragm against the buckets 2. The number in each group will be determined by the volume of steam to be delivered to the wheel or a portion of it. In some instances these groups extend over and supply only a portion of the circumference of the wheel, while in others they extend entirely around its circumference. The individual members of each group are identical in structure. Each comprises two lateral or side walls 10, the outer faces of which conform or approximate in shape to the inner faces of the holders but are preferably not in direct contact with said faces, a small clearance being provided between them to avoid the necessity of accurate fitting. The outer faces of the walls 10 extend straight downward from the flanges and may usually be plane surfaces because of the relatively large diameter of the holders. Connecting the front edges of the lateral walls 10 is a transverse wall 11, Fig. 1, preferably of substantially uniform thickness, which curves downward from the upper face of the nozzle and is continued from the end of the curve in a substantially straight direction at a suitable angle to the lower face of the nozzle. The rear edges of the lateral walls are unconnected and conform in their general shape to that of the transverse wall 11, so that when the individual nozzle members are grouped in nested relation, Fig. 1, the front face of one wall 11 forms the rear wall of the nozzle passage 12, while its rear face forms the front wall of a similar nozzle passage 13. The terms front and rear as applied to the wall 11 and the edges of the wall 10 are merely relative and are used for the sake of convenience in describing the invention. Obviously the transverse wall can join either the front or the rear edges of the lateral walls. Fig. 5 shows a nozzle member having a wall 11' joining the rear edges of the walls 10, the front edges being unconnected. Members of this construction can be grouped or nested in a manner simi-

lar to that shown in Fig. 1. The wall 11 or 11' is in either case common to two of the nozzle passages. The upper edges of the lateral walls 10 are provided with outwardly directed flanges 8 which engage with the shoulders 7 formed on the holders. The form or shape of the nozzle passage can be changed to suit the operating conditions in the particular machine or portion of a machine where the nozzles are employed. This can be readily done by changing the form of the surfaces of the walls 10 and 11 which bound the nozzle passage without affecting the outside of the members. Thus the nozzle may be made expanding or non-expanding as desired.

The nozzle members may be made of cast metal having physical characteristics adapted to meet the conditions to which the nozzle is subjected, or they may be struck up from suitable sheet metal, or drop forged. Little or no machine work will be necessary to finish them ready for use, but if any is required all of the surfaces are readily accessible and can be finished at small expense. This would not be possible in a nozzle having walls completely inclosing the nozzle passage.

In Fig. 4, the holder 14 is provided with a shoulder 15 which engages the lower edges of the nozzle members and assists in supporting them. This construction will be found advantageous under certain conditions, but ordinarily the structure shown in Fig. 2 will be very satisfactory.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

1. A turbine nozzle comprising a support, and a group of nested, individual nozzle members mounted on the support, each member having two lateral walls spaced apart and provided with flanges which project outwardly adjacent the upper edges of said walls only and engage the support, the elements of the surface forming the outer face of each wall being straight lines extending

downward from the flange, and one transverse wall joining the two lateral walls which is common to two adjacent nozzle passages.

2. A turbine nozzle comprising a support and a group of nozzle members mounted on the support, each member having two lateral walls provided with flanges along their upper edges only which engage said support, there being a clearance space between said walls and the support, and one transverse wall joining two opposite side edges of the lateral walls, the other two opposite side edges of said walls being unconnected and parallel to the outer face of the transverse wall so that the members may be grouped with the unconnected edges of one member in engagement with said face on the next member to form a nozzle passage between said members.

3. A turbine nozzle comprising a group of nested nozzle members, each member having two lateral walls with their upper edges parallel to their lower edges, flanges projecting outwardly at right angles from the upper edges only of said walls, a transverse wall connecting two opposite side edges of the lateral walls, the other two opposite side edges being unconnected, and said transverse wall being common to two adjacent nozzle passages, and a holder for said members having an opening in which the group is located, shoulders at one side of the opening with which said flanges engage, and other shoulders at the opposite side which engage and support the lower edges of the lateral walls.

4. A turbine nozzle comprising a group of nested, individual nozzle members, each member having two parallel side walls provided with flanges which project outwardly along their upper edges only, the elements of the surface forming the outer face of each of said walls being straight lines extending downward from the flange, and a transverse wall connected to the side walls which is common to two adjacent nozzle passages, a support, a holder for said member which engages at least one of its flanges, and means for securing the holder to the support.

In witness whereof, I have hereunto set my hand this 27th day of March, 1908.

THOMAS BROADBENT.
